DESIGN FOR AN INSIGNIA EXHIBITOR

Roy E. Tilford, Garland, Tex.

Application December 3, 1945, Serial No. 124,274

Term of patent 3½ years

(Cl. D80—9)

To all whom it may concern:

Be it known that I, Roy E. Tilford, a citizen of the United States, residing at Garland, in the county of Dallas and State of Texas, have invented a new, original, and ornamental Design for an Insignia Exhibitor, of which the following is a specification, reference being had to the accompanying drawing, forming part thereof.

I claim:

The ornamental design for an insignia exhibitor, as shown.

ROY E. TILFORD.
